UNITED STATES PATENT OFFICE.

CHARLES A. GORDON, OF BONNER SPRINGS, KANSAS.

VEGETABLE-CUTTER.

SPECIFICATION forming part of Letters Patent No. 558,063, dated April 14, 1896.

Application filed July 22, 1895. Serial No. 556,774. (No model.)

To all whom it may concern:

Be it known that I, CHARLES A. GORDON, a citizen of the United States, residing at Bonner Springs, in the county of Wyandotte and 5 State of Kansas, have invented certain new and useful Improvements in Vegetable-Cutters; and I do declare the following to be a full, clear, and exact description of the invention, such as will enable others skilled in the 10 art to which it appertains to make and use the same.

My invention relates to vegetable-cutters, and more particularly to devices for cutting potatoes in proper shapes for cooking and 15 planting.

The object of the invention is to provide a cutter which shall be simple of construction, durable in use, and comparatively inexpensive of production.

20 With these objects in view the invention consists of certain features of construction and combination of parts, which will be hereinafter fully described and claimed.

In the accompanying drawings, Figure 1 is 25 a longitudinal vertical sectional view of my improved vegetable-cutter. Fig. 2 is a detail perspective of one of the cutting-cylinders removed from the frame. Fig. 3 is a sectional view taken longitudinally through the axis 30 of the same. Fig. 4 is a detail perspective of one of the longitudinal cutting-knives. Fig. 5 is a similar view of one of the circular cutting-knives, and Fig. 6 is a view of the adjustable longitudinal dividing-knife.

35 In the drawings, 1 represents the supporting-casing, having at its upper end a feed-hopper 2 and at its lower end a discharge-tube 3. Journaled upon shafts 4, mounted in bearings of the frame, are two cutting-cylinders 5.

40 Each of these cylinders consist of circular knives 6, having in their peripheries, at equal distances apart, notches 7, and being provided with spokes 8 and hubs 9, by means of which they are keyed to the shaft aforesaid.

45 Extending at right angles to the circular knives are longitudinal knives 10, which have notches 11, which correspond to and fit into the notches of the circular knives. The inner circular knife, instead of being provided with

50 notches, is provided with an aperture 12, which receives the inner tenoned ends 13 of the longitudinal knives, while their outer ends

fit between parallel lips 14, which project from the inner side of a gear-wheel 15, which is keyed upon the shaft, and split pins 16 serve 55 to hold the longitudinal knives between the lips. The gear-wheels of the two cutting-cylinders mesh, and one of the supporting-shafts is provided with a crank 16', by turning which the cutting-cylinders will be rotated in opposite directions toward each other, as indicated by the arrow in Fig. 1.

Immediately above the point where the cutting-cylinders nearly approach each other is an adjustable longitudinal knife 17. As 65 shown in the drawings, this knife is made adjustable by a set-screw 18, but any other suitable means may be employed.

Arranged upon each of the shafts of each of the cutting-cylinders between the hubs of 70 the circular knives are spacing-sleeves 20, which serve to hold the knives spaced apart and prevent them becoming displaced or out of proper relation with each other. Shoulders 21 are formed near the outer ends of each 75 of the shafts at the inner side of the casing, and washers 22 and nuts 23 are placed upon the inner ends of the shafts, by means of which the circular knives may be firmly clamped between said washers and shoulders 80 and the parts firmly held together.

In operation the vegetables to be cut are placed into the hopper and are fed directly to the cylinders. The longitudinal knives of the cylinders will cut the vegetables longitudinally, while the circular knives will cut them transversely. The central adjustable knife will also give the vegetables an additional longitudinal cut, so that there will be no liability of a potato passing through the 90 machine without being properly sliced.

The device is exceedingly simple, and will be found to be very useful in preparing vegetables for cooking purposes for hotels and large boarding-houses, for which it is particularly adapted.

From the foregoing description, taken in connection with the accompanying drawings, the operation and construction of the invention will be readily understood without requiring further explanation.

Having thus described my invention, what I claim, and desire to secure by Letters Patent, is—

1. In a vegetable-cutter, the combination with a main frame or casing, of rotary cutters mounted therein, and consisting of longitudinal knives arranged in the general form of a cylinder, and circular knives secured to said longitudinal knives, the cutters being provided with intermeshing gear-wheels arranged adjacent to each other, and a longitudinal knife supported between said cutters in close relation and to act conjointly therewith, and means for rotating the cutters, substantially as set forth.

2. In a vegetable-cutter, the combination with a main frame or casing and shafts journaled in said casing, of cutters consisting of circular knives having hubs, which are journaled on said shafts, several of the circular knives being provided with notches in their

edges, while the innermost knife is provided with apertures, a gear-wheel having parallel lips projecting inwardly therefrom, longitudinal knives having notches in their lower edges, which engage the notches of the circular knives, and provided with a tenon which projects through the apertures in the inner knife, the outer ends of said longitudinal knives being located between the lips of the gear-wheel and split pins for securing them therein between, substantially as set forth.

In testimony whereof I affix my signature in presence of two witnesses.

CHARLES A. GORDON.
